UNITED STATES PATENT OFFICE.

THOMAS SUTCLIFFE AND JOHN MARSHALL, OF PAWTUCKET, R. I.

LOOM-SHUTTLE.

SPECIFICATION forming part of Letters Patent No. 350,953, dated October 19, 1886.

Application filed February 20, 1886. Serial No. 192,616. (No model.)

To all whom it may concern:

Be it known that we, THOMAS SUTCLIFFE and JOHN MARSHALL, subjects of the Queen of England, residing at Pawtucket, in the county 5 of Providence and State of Rhode Island, have invented a new and useful Loom-Shuttle, of which the following is a specification.

Our said invention relates to an improved means for securing the spindle in the shuttle-frame and yet permitting the spindle to be 10 easily and quickly removed.

The invention consists in certain novel features of construction, which will first be described with reference to the drawings and 15 then clearly pointed out in the claim.

The accompanying drawings are hereby made part of this specification, similar letters of reference thereon indicating corresponding parts.

Figure 1 of said drawings is a longitudinal sectional elevation of a shuttle having our said improved means for holding the spindle, the spindle being shown in the center of the shuttle and carrying a filled bobbin. Fig. 2 is a 25 longitudinal section, partly in elevation, of one end of a shuttle, showing the spindle raised. Fig. 3 is a detached view of the exterior side of said swinging lever, and Fig. 4 is an end view of the same. Fig. 5 is a detached view 30 of the spindle, showing the grooved slots at its end.

a a show the shuttle-frame; *b*, the bobbin; *c*, the spindle; *d*, a shoulder on the spindle having the deepened groove *e*. *f* is a like groove 35 at the end.

h is the peculiarly-shaped lever, longitudinally perforated, as seen at *i*, to receive the slotted end of the spindle, as seen in Fig. 1, and also transversely grooved, as at *e*. *k* shows 40 a fulcrum for said lever, and *m* a strengthening-arm.

n o respectively show fitted pins or rests for the spindle when locked in the shuttle, as hereinafter described.

r is a flattened spring held by the screw *s*, and bearing upon and keeping in place the lever *h*, as seen at *t*. *u* shows the thread unwinding from the bobbin.

The mutual relation and the combined use 50 of these several parts will readily appear from the drawings. The end sought is to keep the spindle and bobbin firmly in their places, and to greatly prolong the time they may be used without changes or repairs. The spindle is

taken from the shuttle by turning the lever *h* 55 up into the position shown in Fig. 2, when the spindle will easily slide out of said lever. The bobbin is placed on the spindle while the latter is so removed. To replace it the end of the spindle is inserted in the central perforation, *i*, of said lever, and is pushed down until the shoulder *d* reaches a similar shoulder inside the perforation, and seen at *x* in Fig. 1. When the lever is swung back into place, the spindle and bobbin will lie in the 60 center of the shuttle, as in Fig. 1, the slotted groove *e*, registering with groove *e'* in lever *h*, will interlock with the pin or spindle rest *n*, and the slotted groove *f* with the rest or pin *o*, the spring *r* preventing any unlocking of 65 these parts until the lever *h* is again lifted by taking hold of the spindle or bobbin. When the parts aforesaid are interlocked, as described and shown, great firmness and steadiness of the spindle and of the bobbin thereon 70 are secured, and the spring *r* and the arm *m* of the lever *h*, lying squarely against the part *y* of the shuttle-frame, contribute to prevent the wavering and wearing of the spindle heretofore incident to its use. The frame of the 75 bobbin may or may not have the end *z*, as preferred, the button-shaped end *c'* of the spindle being sufficient to firmly hold the bobbin in place in either case.

Having thus described our said invention, 80 what we claim as new, and desire to secure by Letters Patent, is—

The combination, with a shuttle-frame provided with spindle-rests *n o*, and having a receding wall, *y*, of a longitudinally-perforated lever hinged in one end of said frame, and having a transverse groove, *e'*, in its under side, and also having a laterally-extending arm, *m*, for engagement with wall *y* when the lever is down, a spring for holding the lever down, and a bobbin-spindle, one end of which is adapted to be passed through the lever, and in which are formed transverse grooves *f e*, one of said grooves engaging with the under side of rest *o*, and the other groove registering with groove *e'* in the lever and engaging with the top of rest *n*, substantially as described.

THOMAS SUTCLIFFE.
JOHN MARSHALL.
